UNITED STATES PATENT OFFICE.

LZ ADAM BROWN, OF ALTO, MICHIGAN.

DESIGN FOR A PNEUMATIC RUBBER TIRE.

Application filed June 5, 1924. Serial No. 9,802. Term of patent 14 years.

To all whom it may concern:

Be it known that I, LZ ADAM BROWN, a citizen of the United States, residing at Alto, in the county of Kent and State of Michigan, have invented a new, original, and ornamental Design for Pneumatic Rubber Tires, of which the following is a specification, reference being had to the accompanying drawings, forming a part thereof, in which:—

Figure 1 is a perspective view of pneumatic rubber tire showing my design; and Figure 2 is a radial sectional view of the same.

I claim:

The ornamental design for a pneumatic rubber tire substantially as shown.

LZ ADAM BROWN.
